EDWARD G. KASTNER AND JOHN E. BENTON, OF DETROIT, MICHIGAN.

COIN-HANDLING DEVICE.

1,111,389.

Specification of Letters Patent. Patented Sept. 22, 1914.

Application filed October 6, 1913. Serial No. 793,502.

To all whom it may concern:

Be it known that we, EDWARD G. KASTNER and JOHN E. BENTON, citizens of the United States, residing at Detroit, county of Wayne, 5 State of Michigan, have invented a certain new and useful Improvement in Coin-Handling Devices, and declare the following to be a full, clear, and exact description of the same, such as will enable others skilled 10 in the art to which it pertains to make and use the same, reference being had to the accompanying drawings, which form a part of this specification.

This invention relates to coin handling 15 devices of that type frequently used by street-car conductors and others in providing the change for a coin of larger denomination than is required in the payment of a fare or purchase of a ticket or other article 20 and, an object of the invention is a simple and inexpensive structure for the purpose mentioned and that is more compact in form than the usual device for the purpose.

A further object is in the provision of a 25 delivery tube or chamber arranged in such manner and of such form that coins extracted from the tube fall on edge and roll to the delivery opening of the chamber instead of sliding side-wise as is sometimes the case. 30 Devices of this nature are usually carried upon the person of the operator by means of a belt or otherwise, and in addition to the compactness of form mentioned it is an object to provide a device for the purpose 35 that is light in weight and in which the operating fingers of the coin extractors are held from contact with the clothing of the operator and therefore readily accessible.

These and other objects and novel features 40 of construction are hereinafter more fully described and claimed and shown in the accompanying drawings in which—

Figure 1 is a plan view of a coin handling device embodying our invention. Fig. 2 is a 45 front elevation thereof partly in section. Fig. 3 is a vertical section of one of the larger coin holding tubes. Fig. 4 is a section of one of the coin holding tubes provided 50 with means for extracting one or two coins therefrom at will. Fig. 5 is a bottom view of part of the device. Fig. 6 is a detail showing one of the extractors.

Similar characters refer to similar parts 55 throughout the drawings and specification.

As may be seen more clearly in Fig. 3, there is an upper plate 1 and a lower plate

2, in apertures in which the upper and lower ends of each tube are secured respectively. The open upper ends of the tubes are normally closed by a cover plate 3 provided with 60 slots 4, 5, 6, 7 and 8 for the tubes 9, 10, 11, 12 and 13 respectively, and as may be seen in Fig. 1, each of the slots is provided at the rear side with an up-standing flange 14, whereby the operator, in inserting a coin 65 into its respective tube, may draw the coin back in contact with the cover until it engages this flange thereby determining, without the necessity of actually looking, when the coin is in position to be deposited. This 70 cover plate is preferably provided with two, ring shaped, hinged members 15, the ends of which are not entirely closed providing an open space as shown in Fig. 4 between the ends thereof. One end of each ring is fastened to the cover and extends through an aperture provided in the upper plate 1 and by lifting the cover the ring is drawn through the opening in the plate. If the cover be turned to the position shown by 75 dotted lines in Fig. 4, the free end of the ring may be lifted out of the aperture in the plate and the cover removed, but when upon the person of the wearer the cover may not be turned to such extent as to allow it to be 80 removed although the cover may, nevertheless, be raised to a sufficient extent to allow a stack of coins to be inserted in the proper tube.

A spring catch 16 is secured to the plate 80 1 and is provided with a lip or extension 17 to engage over the cover plate and hold it in place. As may be seen in Fig. 1, the cover plate 1 is cut away at 18 at each of the back corners exposing the plate 1 at that point. 95 Secured in the rear corners of the lower plate 2 is a wire hook 19 which extends upward from the lower plate through an aperture provided in the exposed corners of the plate 3, then is bent downward forming a 100 hook end 20 that may be utilized to hang the device on a belt or clothing worn by the operator.

The general operation of the device may be understood from an examination of Fig. 105 3, in which an extractor plate 21, of the general form shown in Fig. 6, is positioned at the bottom of the tube so that the lowermost coin rests in the opening 22 of the extractor. By moving the extractor forward 110 toward the delivery channel or chamber 23, the lowermost coin is moved forward, as

shown by dotted lines in said figure, and the forward end when the extractor has been moved a sufficient distance begins to fall. The inside wall of the delivery chamber is curved, as shown at 24, against which the flat side of the coin engages as it falls from the extractor and in falling from this position by gravity it assumes a substantially perpendicular position, as is also shown by dotted lines, whereby it may roll edgewise down the channel to the delivery opening 60 therein, near the center from which it is received in the hand of the operator. This arrangement provides for a more sure and rapid delivery of the coin than if allowed to slide upon its flat surface. The manner of rolling of the coin is shown more clearly in Fig. 2 at the left hand side of the figure. Each extractor 21 is provided with a depending operating finger 25 spaced from the rear side of the device, as may be seen more clearly in Figs. 3 and 4. The lower plate 2 at the rear edge is provided with an upturned portion 26 to which a depending plate 27 is secured that contacts the clothing of the wearer and holds it from folding, or otherwise preventing easy access to the operating fingers 25. Each of the extractors operates between the lower plate 2 and a holding plate 28 extending entirely across the bottom of the device and the extractors are held in retracted position below the tube by springs 29 in each instance. In order that the tubes may be set very close together and compactness secured, the extractors are arranged to overlap as may be seen more clearly in Fig. 2. The extractor arms for the tube 9 are shown at 30, 30 and the next succeeding tube 10 is made longer than the tube 9 extending a slight distance through the plate 2 and one arm 31 of the extractor for the tube 10 is placed directly below an arm 30 of the extractor for the tube 9 and the other arm 31 is placed beneath an arm of the extractor for the tube 19 which arrangement alternates throughout the series of tubes. The plate 28 is so formed as to engage the lower surface of each extractor as may be seen in said Fig. 2 and is secured at each end to the lower tube plate 2; this plate 28 is slotted at 32 substantially on a center line of each tube to allow the operating finger 25 to be moved forward in extracting a coin. The upper edge of the opening in each extractor is preferably beveled, as shown at 35 in Fig. 6, the purpose of which is to prevent any single actuator from extracting more than the required coin from the stack as it sometimes happens that a coin considerably thinner than usual is inserted in the device and eventually falls into the extractor which would allow the next succeeding coin to project into the opening in the extractor a slight distance but, by providing

the beveled edge as shown this coin will be forced upward into the stack in operating the extractor and the extractor allowed to pass beneath ejecting the thin coin in the proper manner.

Fig. 1 shows a device with tubes 9 and 10 adaptable for use with the ordinary 5-cent piece, the tubes 11, 12 and 13 being for a dime, quarter and one-half dollar respectively, but it is to be understood that the tubes may be arranged in any approved manner and a greater or less number of tubes used as may be desired, or altered in other specific relation one to the other without departing from the spirit of this invention.

In many instances it is desirable to return two dimes in making change and in other instances it is desirable to return but a single dime. We have, therefore, arranged the dime tube with two extractors 40 and 41, the extractor 40 lying upon the upper surface of the extractor 41. The operating finger for the extractor 41 is located substantially centrally of the tube as is all other finger hooks 25 with the other tubes, but the finger hook 42 of the extractor 40 is spaced between the finger hooks of the dime tube and the five cent tube, but in line with said other finger hooks. The extractor 40 is double the thickness of the extractor 41 so that in the operating thereof two dimes are removed from the stack in the tube while the dime in the extractor 41 remains in place in the extractor which is held in retracted position by the spring 43. The dime in the extractor 41 is held in place by reason of the ends of the extractor arms extending about the edge of the coin beyond the center thereof, as may be seen in Fig. 5. By this arrangement one or two dimes may be removed from the tube by a single operation at the will of the operator.

From the foregoing description it is evident that the device is very simple in construction, compact in form and light in weight and is comparatively inexpensive to manufacture.

Having thus briefly described our invention, what we claim and desire to secure by Letters Patent of the United States is—

1. A device of the kind described, comprising a series of coin holding tubes held in closely spaced relation, the upper ends of the tubes terminating in the same plane, a coin extractor at the bottom of each tube adapted to remove the lowermost coin therefrom, the tubes alternating in length whereby the extractor of one tube lies below and in contact with the extractor of the two contiguous tubes of shorter length, and a delivery channel so arranged that coins delivered therein are delivered on edge at a central opening.

2. A device of the kind described, com-

prising a series of coin holding tubes adapted to receive coins of different denominations, an apertured upper and lower plate into which the open upper and lower ends 5 of the tubes extend respectively, the upper ends of the tubes being substantially flush with the upper plate, an extractor at the open lower end of each tube, said tubes alternating in length whereby an extractor 10 for a long tube may operate in contact with the lower surface of the shorter contiguous tubes, thereby enabling the tubes to be positioned in closely spaced relation, a cover hinged to the upper plate provided with 15 coin slots for each individual tube, a spring for each extractor adapted to hold it in retracted position, a delivery channel adjacent the lower ends of the tubes, the said channel being so formed that coins delivered thereinto by the extractors are delivered on edge 20 through a central opening with which the channel is provided.

3. A device of the kind described, comprising a series of coin holding tubes adapted to receive and hold coins of different denominations in individual stacks, an apertured upper and lower plate into which the upper and lower open ends of the tubes extend respectively, the upper ends of the tubes 25 being substantially in the same plane, a cover plate hinged to the upper apertured plate for the tubes, said cover plate having coin slots for each tube, the rear edge of which is provided with an upstanding 30 flange, an extractor at the lower end of each tube, said tubes alternating in length whereby an extractor for a long tube may operate in contact with the lower surface of the extractors for the shorter contiguous tubes 35 40 thereby enabling the tubes to be positioned in closely spaced relation, a spring for each extractor adapted to hold it in retracted position, and a delivery channel for receiving coins from the extractors, said channel being provided with a central delivery opening.

4. A device of the kind described, comprising a series of coin holding tubes adapted to receive and hold coins of different 45 denominations in individual stacks, there be-

ing a plurality of tubes for the coin of lowest denomination, an apertured upper and lower plate into which the upper and lower ends of the tubes extend respectively, the upper ends of the tubes being substantially 55 in the same plane, a cover plate provided with a coin slot for each tube hinged to the upper apertured plate for the tubes, an extractor for each tube at the lower open end thereof, each adapted for the removal of 60 a single coin from its respective tube, said tubes alternating in length whereby an extractor for a long tube may operate in contact with the lower surface of the extractors for the shorter contiguous tubes whereby the 65 tubes may be positioned in closely spaced relation, an operating finger for each extractor extending therebelow, a delivery channel into which the extractors deliver the coins, the delivery end of the channel extending below the device a distance not less than the length of the depending operating fingers, and a plate extending from the back of the device and spaced from the operating fingers, said plate extending below 70 75 the device a distance substantially equal to that of the delivery channel.

5. In a device of the kind described provided with a series of coin holding tubes adapted to receive and hold coins of different denominations in individual stacks, a plurality of tubes for holding five-cent pieces, a single tube for holding dimes, an extractor operating at the lower end of each tube adapted to extract a single coin from 80 each stack, and an extractor for the dime tube adapted to remove two coins therefrom at a single operation, the upper ends of the tubes terminating in the same plane and alternating in length whereby an extractor 85 at the bottom of one of the tubes may overlap the extractor for each of the contiguous tubes.

In testimony whereof, we sign this specification in the presence of two witnesses.
